(57) **CLAIM**

The ornamental design for an electronic atomizer, as shown and described.

DESCRIPTION

FIG. 1 is a Perspective View of the electronic atomizer;

FIG. 2 is a Left side View thereof;

FIG. 3 is a Right side View thereof;

FIG. 4 is a Rear View thereof;

FIG. 5 is a Front View thereof;

FIG. 6 is a Top View thereof; and,

FIG. 7 is a Bottom View thereof.

The broken lines in the drawings depict portions of the electronic atomizer that form no part of the claimed design.
